DESIGN FOR A FACSIMILE RECORDER OR THE LIKE

William G. H. Finch, New York, N. Y.

Application December 27, 1937, Serial No. 73,885

Term of patent 14 years

To all whom it may concern:

Be it known that I, William G. H. Finch, a citizen of the United States, residing at New York, in the county of Bronx and State of New York, have invented a new, original, and ornamental Design for Facsimile Recorder or the like, of which the following is a specification, reference being had to the accompanying drawing, forming a part thereof.

I claim:

The ornamental design for a facsimile recorder or the like, as shown.

WILLIAM G. H. FINCH.
